UNITED STATES PATENT OFFICE.

THOMAS M. DUDGEON, OF AVALON BOROUGH, PENNSYLVANIA, ASSIGNOR TO THE SUPERIOR MANUFACTURING COMPANY, OF PITTSBURGH, PENNSYLVANIA, A CORPORATION OF PENNSYLVANIA.

DENTAL FURNACE.

Application filed June 25, 1919. Serial No. 306,558.

To all whom it may concern:

Be it known that I, THOMAS M. DUDGEON, a citizen of the United States, and residing in the borough of Avalon, in the county of 5 Allegheny and State of Pennsylvania, have invented or discovered new and useful Improvements in Dental Furnaces, of which the following is a specification.

My invention consists in a furnace for the 10 preparation of molds for dental castings.

The process of forming such molds is as follows. A piece of casting wax is pressed down into the tooth cavity to take an accurate impression of the latter and the protruding portion of the wax is carved and shaped to produce the desired exterior contour of the tooth when filled. Thus what is termed the "model" is formed. The model is then mounted on the sprue, which is a 15 short length of wire, and painted with the investment material. The sprue is now mounted on the sprue holder or crucible former, and the flask or bucket set down on the sprue holder, surrounding the model.

20 The flask is then filled with the investment material, thus embedding the model. The investment material is then allowed to set. Then the sprue holder is warmed and it and the sprue removed from the flask, leaving the hardened mass of investment material with a concaved end and a pouring gate extending downwardly or inwardly to the embedded model. The next step is to evaporate the wax model, thus leaving the mold cavity 25

30 at the inner end of the pouring gate. The evaporation is effected by heating the flask and its contents. In this step the heat must be gradually raised and should not exceed substantially 320° Fahr. If the rise in temperature is too rapid, the wax will boil and steam with the result that the mold cavity will be distended and distorted. If the temperature is excessive, the mold will be burned 35 and the thin carbon skin which should cover the walls of the mold will be destroyed, leaving the walls of the mold cavity rough and porous. If the temperature is not sufficiently high or maintained for a sufficient period, the wax will be incompletely evaporated and 40

45 the mold cavity will be of improper capacity and shape. If the heat has been properly applied the operation of evaporating the wax should be completed in approximately forty-five minutes. Where the wax has been evap-

55 orated too rapidly, the filling subsequently cast in the mold must be ground down to fit the tooth cavity for which it was intended. If the temperature has been too high the surface of the filling will be rough and will require grinding and polishing before 60 it is fit for installation in the tooth. If the temperature has been insufficient to properly evaporate the wax, the cast filling must be thrown aside as useless.

The present practice is to heat the flask 65 over a gas flame, or burner, and it is quite evident that constant watching and great skill is necessary to obtain evenly a fairly satisfactory mold.

It has been estimated that in the case 70 of the average operator approximately 90% of his fillings are either unusable or must be ground and polished before they can be put in place in the tooth.

The object which I have in view is the 75 provision of a furnace or apparatus for heating the flask and evaporating the wax model in such a manner that the mold will be perfect and an accurate negative of the model, with its walls properly coated with the carbon film. I effect this object by providing 80 means whereby the rise in temperature is sufficiently slow to avoid the boiling or steaming of the wax, while in due time the proper maximum temperature is attained to 85 thoroughly evaporate the wax without burning the mold or injuring the carbon film which should coat its walls. But this temperature is never exceeded, so that the mold 90 cannot be injured by leaving the flask over time in the furnace. The result is that the molds produced in my improved furnace are 95 perfect and the fillings subsequently cast therein are ready for installation in the tooth cavities without requiring any grinding or polishing.

Many other novel features of construction and arrangement of parts will appear from the following description.

In the accompanying drawings, which are 100 merely intended to illustrate a practical embodiment of the principles of my invention in a furnace wherein gas is used for fuel, and not to limit the scope of the former to the structure shown, Fig. 1 is a perspective 105 of the furnace; Fig. 2 is a vertical section of the same; Fig. 3 is a top plan view of the oven portion of the furnace with the top clo-

sure removed and the oven lining in place. Fig. 4 is a top plan view of the combustion chamber with the oven removed, and Fig. 5 is an enlarged perspective of the oven lining member.

The following is a detailed description of the drawings.

The furnace shown is rectangular in cross section and comprises three main elements which are detachably fitted together. A is the base containing the combustion or heat chamber, B, the oven, and C the top closure; all preferably formed of metal or other suitable material.

15 The base A consists of an open top box having perforated vertical walls 1 and floor 2. The floor is provided with a protective layer 3 of heat insulating material, such as asbestos, and 4 represents air ports extending through said floor and asbestos sheet. The top edges of the walls 1 are turned inwardly in a horizontal plane and then vertically, as shown more clearly in Fig. 2, forming an L-shape flange to support the 25 oven member.

5 are the angle shape legs secured to the exterior corners of the walls 1 and extending slightly above the same, as shown. Near their lower ends the legs 5 support the horizontal shelf 6 upon which is mounted the Bunsen burner D whose top extends up into the combustion chamber, as shown. 7 is the gas supply pipe leading under the shelf 6 to the burner D, and provided with a regulating valve 8 provided with an indicating finger 9 which moves over a fixed dial 10. The combustion chamber is provided with a lighting hole covered by the swing plate 11.

The oven B conforms in cross section to 40 that of the combustion chamber, having vertical walls 12 having an inturned bottom flange which fits into the L-shape flange on the top of the combustion chamber, the upper ends of the legs 5 assisting in holding 45 the parts together. The floor 13 is somewhat elevated and has a downwardly turned edge flange which rests on the bottom flange of the side walls of the oven. The floor is preferably riveted to the side walls. Above 50 the floor the side walls are provided with an interior lining 12^a of asbestos. The top edges of the walls 12 are inclined inwardly, as shown, to receive and support the top closure C. The floor 13 is provided around 55 its end and rear edges with a row of open ports 14 for the upward passage of the products of combustion.

E is the removable oven lining member which may be conveniently bent up of sheet 60 metal in substantially the form shown in Fig. 5, having vertical end walls 15 and rear wall 16 while corner braces or spacers 17 are formed by doubling the metal, and at the front the end walls are bent outward to 65 form the flanges 18. The top edges of the

end and rear walls are inclined inwardly substantially parallel with the inclines of the walls of the oven. Thus, when the oven lining is in position, as shown in Fig. 3 vertical flues are formed, in the ends and rear 70 of the oven, into the bottoms of which open the ports 14 while the tops of the flues are open and turn inward owing to the inclination of the top of the oven and oven lining walls. The spacers 17 extend into and fit 75 the rear corners of the oven and the flanges 18 fit into the front corners of the same, thus holding the lining snugly in place.

The front wall of the oven is provided with a rectangular doorway 19 which preferably extends across nearly the entire width of the oven, and is provided with an externally mounted sliding door 20 provided with an internal lining of asbestos 21.

One end wall 15 is provided with a circular aperture 22 which is alined with a similar aperture in the end wall of the oven. F is a thermostatic device mounted in said aperture in the oven wall, and is thus subjected to the oven heat through the aperture 22. For this purpose I prefer to use an oven thermometer which will enable the oven heat to be read. 23 is the pointer working on the curved dial 24, and 25 is an arm rigid with or moving in unison with the pointer 23 and extending through a slot 26 cut in a circumferential direction in the thermometer case.

The top closure C is of proper contour to fit down on the open top of the oven and 100 form a dome for the flues and oven compartment.

Thus, it is shown in the form of a truncated pyramid having a depending flange 27 which slips down over the oven walls. The 105 throat 28 of the closure is preferably cylindrical and provided with a flap valve 29 hinged at one side. 30 is a lever extending rigidly from said flap valve for operating the same. The outer end of said lever is bent to form a loop through which extends a link 31 whose lower end is pivotally attached to the arm 25. 32 is a pierced ball slipped on said link and resting on the end of the lever 30. The upper end of the link 110 31 is threaded and provided with a thumb nut 33. It is evident that as the temperature of the oven rises, and the pointer 23 moves toward the right on the dial 24, the arm 25 will swing downwardly, drawing down the link 31, and when the nut 33 strikes the ball 32, the lever 30 will be drawn down and, as the temperature rises, the flap valve will be gradually opened. It is also evident that the heat from the combustion chamber will pass 115 upwardly through the flues into the interior of the top closure. Thus the oven will be uniformly heated at the bottom and sides, and will be automatically ventilated by means of the flap valve.

When a wax model is to be evaporated to form a mold, the flask containing the investment material and model, prepared as already described, is placed in the oven and 5 its door closed. The valve 8 is now opened to the proper degree dictated by the gas pressure in the pipe. The thumb nut 33 is adjusted so that the heating of the oven will be gradual to avoid boiling or steaming 10 the wax. Thus I prefer to adjust the nut so that the flap valve will begin to open at an oven temperature of, say, 100° Fahr. Thus the heat will rise more gradually. As the heat increases, the flap valve will 15 gradually open wider to increase the ventilation and render the rise in oven temperature gradual. When the maximum temperature, approximately 320° Fahr. is attained, the flap valve should be open sufficiently to prevent any further substantial 20 increase in the internal heat of the oven. Thus the gas pressure must be taken into consideration, so that the proper amount of gas will be supplied to the burner to 25 furnish sufficient heating power to gradually raise the oven temperature to the maximum desired but not such an excess that the oven heat can be increased beyond the safe maximum. Thus when a furnace is installed the 30 nut 33 should be adjusted and the proper position of the gas valve determined, so that thereafter, when a wax model is to be evaporated, the flask may be inserted in the oven and the door closed, and then the 35 gas valve opened to the degree found to be proper and the burner lighted.

Any other convenient heating agent than a gas burner, such, for instance, an electrical heater may be used.

40 The evaporation process usually takes, in my improved furnace, approximately forty-five minutes, during which time the oven heat gradually reaches the maximum and maintains the same for a period sufficient to 45 properly form the mold. During the operation no care or attention is required, and therefore the dentist or other operator may give his undivided attention to other work, and should he neglect to remove the flask at 50 the termination of the proper time, no injury will result, as the safe maximum temperature can not be exceeded and the mold will be found, when removed, in the same

perfect condition as it had attained to at the end of the forty-five minutes. 55

It is thus evident that no particular skill or experience is required, and as the furnace can be manufactured and sold at moderate cost and contains nothing liable to become impaired, a dentist with even a very limited 60 practice will find it a valuable possession.

In use, my invention has proved itself very advantageous, the molds being accurately formed with smooth carbon filmed walls, and the filling or castings therefrom 65 have fit properly into spaces or cavities for which they were intended without preliminary grinding or polishing.

What I desire to claim is:

1. In a dental furnace for the purposes 70 described, the combination of a burner chamber, an outer casing superimposed on said burner chamber and provided with an inwardly contracted top; an oven in said casing closed off from the latter on its bottom and sides but having a top open to the contracted portion of said casing, heating means in said burner chamber, a valve in the contracted top of said casing, and thermostatic means subjected to the internal 80 heat of said oven and controlling said valve.

2. In a dental furnace for the purposes 85 described, the combination of a base containing a heating chamber and having an open top, a source of heat in said base, an open top, oven member, having a bottom, detachably mounted on said base, said oven bottom being provided with ports along the walls of the oven for the upward escape of 90 heat from said heating chamber, a false oven 95 removably mounted in said oven member having vertical walls spaced from the walls of said oven member bent at the back corners to form integrally connected flanges whereby vertical flues are formed connecting at their lower ends with said ports, a top dome closure removably mounted on said oven member into which the upper ends of said flues and of the false oven open, a valve 100 for the throat of said dome, and thermostatic means actuated by the internal heat of said oven controlling said valve.

Signed at Pittsburgh, Pa., this 20th day of June, 1919.

THOMAS M. DUDGEON.
